(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the portion, labeled '8' of FIG. 1;

FIG. 9 is an enlarged view of the portion, labeled '9' of FIG. 1;

FIG. 10 is an enlarged view of the portion, labeled '10' of FIG. 1;

FIG. 11 is an enlarged view of the portion, labeled '11' of FIG. 1; and,

FIG. 12 is an enlarged view of the portion, labeled '12' of FIG. 6.

The even-dash broken lines illustrate portions of the notebook computer that form no part of the claimed design. The long-dash short-dash lines in FIGS. 1, 6 and 8-12 represent the extents of the detail views and form no part thereof. The oblique line shading shown in the drawings indicates a transparent surface.
